Ebenezer Steele No. 30

The schedule referred to in the Letter Patent recently granted
part of the same containing a description in the words
of the said Ebenezer Steele himself of his improvement
in Saddles and Horse Collars.

To all to whom it may concern be it known
that I Ebenezer Steele of the City County and
State of New York have invented a new and useful
improvement in the manner of constructing Saddles
and Horse Collars in which I substitute that few
feet of elastic leather in place of stitching for the
comparatively rigid and inelastic materials
hitherto employed. And I do hereby declare that
the following is a full and exact description there
of. — The object in view is to interpose an
elastic leather between the saddle materials which form the frame
and the more delicate parts of saddles and horse
collars and these parts of the article bear upon
the animal. As the greatest part of the manner of
making these articles I do not profess to have made
any improvement, all that I propose to do being
merely to omit the ordinary stitching in the bear-
ing parts and to cover them with leather. This
leather is rendered impervious to air by means
of India rubber or otherwise so forming and fix-
ing such covering so that when inflated by means
of a condensing syringe, the bearing parts will be
completely isolated and afford the intended for-
mer.

The more delicate part of the article are opening
provided with a valve must be made for the pur-
pose of attaching the syringe. The manner
in which the air tight covering is to be attached does
not admit of a particular description as

as it may be varied in numerous ways, and must be left to the judgment and fancy of the workman who if skillful will be at no loss in this particular.

What Orlane as a material is nearly the substance of air for other materials in forming a stuffing for the bearing parts of Saddles and Horse Collars
